TIRE FOR A VEHICLE WHEEL

Brian Howard Holmes, Birmingham, and Clive Flint,
Sutton Coldfield, England, assignors to Dunlop Limited

Filed June 29, 1973, Ser. No. 375,179

Claims priority, application Great Britain Jan. 19, 1973

Term of patent 14 years

Int. Cl. D12—15

U.S. Cl. D12—142

FIG. I.

FIG.2.

FIG. 3.

FIG. 1 is a perspective view of a tire for a vehicle wheel showing our new design, it being understood that the tread pattern is repeated throughout the circumference of the tire;

FIG. 2 is a plan view thereof;

FIG. 3 is a typical side elevational view thereof.

We claim:

The ornamental design for a tire for a vehicle wheel, as shown and described.
